(57) **CLAIM**

The ornamental design for an agricultural multi-objective power cart, as shown and described.

DESCRIPTION

FIG. 1 is a perspective view of the agricultural multi-objective power cart of my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The portions of the vehicle shown in broken lines are for illustrative purposes only and form no part of the claimed design.

The agricultural multi-objective power cart of this design is a power vehicle which can load and transfer goods something like agricultural products and workers in agriculture environment like a dirt road or a field in which it is difficult for general vehicles to enter or operate. A front part of engine bonnet comprises head-light and air venting, a middle part of engine bonnet comprises a driver's seat and a frame structure for preventing from overthrow, a rear part of engine bonnet comprises a cargo box. Especially, left/right body panel of seat in the middle part comprises a grill for smoothly cooling of powering part.
